US0D1062761S

(12) **United States Design Patent** (10) Patent No.: US D1,062,761 S
Chuang et al. (45) Date of Patent: ** Feb. 18, 2025

- (54) **DISPLAY SCREEN OR PORTION THEREOF WITH GRAPHICAL USER INTERFACE**

(71) Applicant: **Acer Incorporated**, New Taipei (TW)

(72) Inventors: **Ching-Yuan Chuang**, New Taipei (TW); **Chung-Hsien Lee**, New Taipei (TW); **Cheng-Yi Chang**, New Taipei (TW)

(73) Assignee: **Acer Incorporated**, New Taipei (TW)

(**) Term: **15 Years**

(21) Appl. No.: **29/853,345**

(22) Filed: **Sep. 15, 2022**

(51) LOC (15) Cl. **14-048**

(52) U.S. Cl. **D14/483**

(58) **Field of Classification Search**

USPC **D14/485-493**

CPC **G06F 3/048-0489**

See application file for complete search history.

CLAIM

The ornamental design for a display screen or portion thereof with graphical user interface as shown and described.

DESCRIPTION

The FIGURE is a front view of a display screen or portion thereof with graphical user interface showing our new design.

The dot-dash broken line illustrates a display screen or portion thereof and forms no part of the claimed design. The even-dash broken lines illustrate portions of the graphical user interface that form no part of the claimed design.

1 Claim, 1 Drawing Sheet
